UNITED STATES PATENT OFFICE

WILLIAM M. SHEEHAN, OF ST. LOUIS, MISSOURI, ASSIGNOR, BY MESNE ASSIGNMENTS, TO GENERAL STEEL CASTINGS CORPORATION, OF GRANITE CITY, ILLINOIS, A CORPORATION OF DELAWARE

RAILWAY CAR UNDERFRAME

Application filed April 18, 1928. Serial No. 270,950.

My invention relates to railway rolling stock and consists in an improved underframe structure, particularly adapted for use in hopper cars. Builders of hopper cars have been 5 constantly striving to increase the capacity of such cars and loads carried by the underframe have been increased accordingly, and it is the main object of my invention to provide an underframe structure which will adequately 10 take care of the increased loading of this type of equipment. Due to the fact that a substantial portion of the bottom of the car must be unobstructed to provide for dumping the load, it is obvious that the framing of such 15 cars presents problems which are not encountered in the construction of underframes for ordinary cars in which center sills can run from end to end.

Some of the detailed objects of my invention are to provide a novel center bearing structure which will permit the use of draft sills or bolsters of maximum depth; to provide adequate support for the center bearing portion of the underframe; to suitably support and brace the portions of the underframe which form supports for the sloping end floors of the car; to provide an improved coupler carrying element adapted to withstand the increased stresses resulting from the use of heavily laden cars; to provide draft sills and side sills of greater strength and to facilitate application of the superstructure to the underframe.

Another object of my invention is to provide a car underframe, of the type referred to, in a one-piece casting, whereby the maximum amount of strength may be obtained with a minimum amount of metal, and in which the framing members will not be weakened by 25 perforations for rivets and bolts, and in which the rigidity of the structure will not be affected by the loosening of securing elements.

In the accompanying drawings which illustrate a selected embodiment of my invention—

Figure 1 is a top view of the longitudinal half of my improved underframe.

Figure 2 is, in part, a longitudinal vertical section taken on the center line of the under-

frame shown in Figure 1, and, in part, is a side elevation of the underframe.

Figures 3, 4, 6, 7 and 8 are vertical sections taken on lines 3—3, 4—4, 6—6, 7—7, and 8—8, respectively, of Figure 1.

Figure 5 is an end view of the striking plate and adjacent portions of the underframe.

Figure 9 is an enlarged vertical section through the center bearing portion of the underframe.

Figure 10 is a bottom view of the structure shown in Figure 9.

Figures 11 and 12 are sections taken on lines 11—11 and 12—12 of Figure 2.

The side members 1 of the underframe are box-shaped substantially throughout their length, as indicated in Figure 8, being deeper throughout the hopper portion of the car than at their ends beyond the hopper. These side members are connected near their outer ends by transverse bolsters 2 which are also box-shaped in cross section, and the inner wall 3 of each bolster curves near its ends toward the center of the car and extends lengthwise of the underframe, as indicated at 4, and merges with a transverse frame member 5 inclined from the vertical and serving as a support for the sloping end floor of the superstructure (not shown). The lower portion of this member 5 is disposed vertically, as indicated at 6 (Figure 2) and the inner wall of the box-shaped side member merges with the inclined member 5. The vertical flange 6 is adapted to meet the end of the hopper door (not shown), and this construction avoids the presence of a gap adjacent to the end of the door which is usually closed by means of supplemental plates secured to the door or underframe, or both.

The door may be mounted on the side member 1 in any suitable manner, such, for instance, as is set forth in my copending application Serial Number 260,996, filed March 12, 1928, now Patent No. 1,745,124, granted January 28, 1930, the box-shaped cross section of the side member readily lending itself to such door mounting. The bottom wall of the side member is provided with

one or more openings 7 adapted to admit rivets and tools for the purpose of facilitating the riveting of door hinge brackets or car side supporting brackets, or other super-
5 structure. The upper wall of the side mem-
ber is similarly perforated, as indicated at 8.
By staggering the openings 7 and 8, riveting
operations for parts fastened to the top and
side walls may be carried on more easily
10 than otherwise, and the section area of the
sill is maintained more nearly uniform.

Box-shaped draft sills 9 extend forwardly
from bolsters 2 and it will be noted that the
outer wall of each draft sill curves outwardly
15 so as to merge with the front wall of the cor-
responding bolster and the latter wall forms
a continuation of the outside wall of the side
member 1. Hence, the side members, bolsters
and draft sills cooperate to form a continuous
20 box section member around the outer contour
of the underframe and this member is pro-
vided with suitable pads P for mounting
superstructure supporting elements.

Longitudinally disposed center sills 10 ex-
25 tend between bolsters 2 and transverse mem-
bers 5. These center sills are spaced a greater
distance apart than draft sills 9 and the inner
walls of draft sills 9 are connected with the
center sills by diagonal webs 11 which ex-
30 tend through the bolster from a point ad-
jacent the follower stop S.

The bolster 2 includes an integral depend-
ing projection 12 adapted to form a center
plate element which will fit into a corre-
35 sponding truck center plate. This element
is detailed in Figures 9 and 10, and is shown
as being fitted with a cup-shaped wear plate
13 which may be renewed at intervals and
which will receive the wear resulting from
40 relative rotation of element 12 and the cor-
responding truck center plate member.

In order to prevent relative rotation of
the element 12 and wear plate 13, I provide
a non-circular recess 14 in the element and
45 a correspondingly shaped projection 15 on
the wear plate. Other forms of recesses and
projections could be used, such as square or
rectangular, or the projecting element could
consist of a lug of restricted diameter
50 adapted to positively engage a wall of the
recess to prevent relative rotation of the
parts. The projection could be provided on
the center plate instead of on the wear plate
and the latter could be provided with the
55 recess.

To suitably reinforce the bolsters adjacent
to the center member, I provide vertical webs
16 extending transversely and longitudinally
of the underframe between the inclined inner
60 walls 11 of the draft sills and the front and
rear walls of the bolster.

The outer ends of draft sills 9 are inte-
grally connected by an upper flange 17 and
by a channel-shaped coupler carrier member
18 which has its web disposed vertically and

its flanges disposed horizontally and extend-
ing inwardly from the end of the car. If
preferred, the coupler carrier can also be
made of I-beam or box section. This ar-
rangement of the coupler carrier adapts the
70 same to resist the increased deflecting loads
due to the buffing and pulling forces caused
by the heavier cars and loads carried thereby.

The outer walls of the draft sills are pro-
vided with elongated openings 21 to permit
75 insertion and longitudinal movement of the
draft keys.

The outer ends of diagonally opposite
draft sills 9 are provided with laterally ex-
tending brackets 19 adapted to mount hand
80 brake rigging (not shown). These brackets
extend outwardly from the vertical outer
wall of the draft sill and are reinforced with
suitable webs 20.

Obviously, variations in the structure other
than those mentioned may be made without
departing from the spirit of my invention,
and I contemplate the exclusive use of such
modifications as come within the scope of my
claims.

I claim:

1. In a car underframe, side sills termin-
inating short of the end of the car, bolsters
connecting said sills, and draft sills extend-
ing outwardly from said bolsters, all of said
sills being box-shaped in cross section and co-
operating to provide a continuous vertical
outer wall for the underframe.

2. A one piece car underframe casting
comprising box-shaped side sills terminat-
ing short of the end of the car, box-shaped bolster
members extending inwardly from said side
sills, and box-shaped draft sills extending
outwardly from said bolster members, said
sills and members providing a continuous in-
tegral vertical outer wall for the underframe.

3. In a hopper car underframe, an end
floor supporting wall inclined from the ver-
tical and terminating in a vertically disposed
flange forming the end of the door opening,
a side sill of box-shaped cross section, the
inner wall of which is vertically disposed and
merges with said flange.

4. In a one piece casting forming an under-
frame for a hopper car, longitudinal mem-
bers, and vertically disposed transverse mem-
bers adapted to form the ends of a hopper
opening and adapted to meet the edges of
doors hinged to said longitudinal members.

5. In a hopper car underframe, side sills
each having spaced vertical walls, a trans-
verse member between said sills for support-
ing an end floor and inclined from the ver-
tical, a bolster between said sills and spaced
from said member and including spaced ver-
tical walls, the outer wall of said bolster ex-
tending to the outer walls of said sills and
the inner wall of said bolster curving near its
outer ends and extending lengthwise of the
underframe to connect with said member.

6. In a hopper car underframe, a box-like side sill adapted to mount a hopper door, there being one or more openings along one wall of said sill to permit access to the inner faces of the sill walls to facilitate riveting separate elements to the sill. 7. In a hopper car underframe, a box-like side sill, there being one or more openings along a horizontal wall of said sill adapted to permit access to the inner faces of the side walls to facilitate the securing of separate elements thereto. 8. In a car underframe, a draft sill, a bolster extending across the underframe at the rear of said draft sill and having spaced vertical walls, a center sill extending inwardly from said bolster and spaced farther from the center line of the car than said draft sill, and a vertical wall extending diagonally from the inner end of said draft sill, adjacent to the front of said bolster, to the outer end of said center sill adjacent to the rear of said bolster. 9. In a car underframe, a bolster with a center bearing member, spaced box-shaped draft sills meeting said bolster and having their inner walls extending through said bolster, and vertically disposed webs extending longitudinally of said bolster intermediate its walls and between said inner draft sill walls and said member. 10. In a car underframe, a bolster with a center bearing member, spaced box-shaped draft sills meeting said bolster and having their inner walls extending through said bolster, and vertically disposed webs extending longitudinally and transversely of said bolster and located over said member between said draft sill walls. 11. A one-piece casting comprising a vehicle underframe with side sills terminating short of the end of the underframe, bolsters extending between the ends of said side sills, draft sills extending from the intermediate portions of said bolsters to the end of the underframe, said sills and bolsters comprising a continuous box-shaped member forming the outer contour of the underframe. 12. A one-piece casting comprising a vehicle underframe with side sills terminating short of the end of the underframe, bolsters extending between the ends of said side sills, draft sills extending from the intermediate portions of said bolsters to the end of the underframe, said sills and bolsters comprising a continuous box-shaped member forming the outer contour of the underframe, there being pads at intervals on said member for mounting superstructure supporting elements. 13. In a railway vehicle underframe, a draft sill, a bolster spaced from the outer end of said draft sill and extending laterally from said draft sill, a side sill terminating at said bolster, and a hand brake bracket spaced from said side sill extending laterally from said draft sill adjacent the outer end of the latter. 14. In a one-piece cast underframe for railway vehicles, a bolster of box-shape cross section, a draft sill of similar cross section extending forwardly from said bolster, a center sill extending rearwardly from said bolster, and transversely extending webs connecting said bolster, draft sill and center sill. 15. In a car underframe, a draft sill, a draft gear follower stop on said draft sill, a transverse bolster at the rear of said draft sill and having spaced vertical walls, a center sill extending rearwardly from said bolster and spaced transversely of the car from said draft sill, and a vertical wall extending diagonally from a point on said draft sill adjacent to said follower stop to the rear wall of said bolster adjacent to said center sill. 16. In a car underframe, side sills terminating short of the end of the underframe, bolsters connecting said sills, and draft sills extending outwardly from said bolsters, said sills and bolsters cooperating to form a continuous vertical wall forming the outer contour of the underframe. 17. A one-piece car underframe casting comprising side sills terminating short of the ends of the underframe, bolsters connecting said sills, and draft sills extending outwardly from said bolsters, vertical webs of said sills and bolsters cooperating to form a continuous vertical wall forming the outer contour of the underframe. 18. A one-piece casting comprising a car underframe and comprising side sills, a transverse member between said sills for supporting an endfloor, a bolster between said sills and spaced from said member and including spaced vertical walls, the outer wall of said bolster extending to the outside of said sills and the inner wall of said bolster curving near its outer ends and extending lengthwise of the underframe to connect with said member. 19. In a car underframe, a draft sill including spaced vertical walls, a bolster at the rear of said draft sill having spaced vertical walls, a center sill at the rear of said bolster and spaced farther from the longitudinal center line of the car than said draft sill, and a vertical web extending through said bolster and connecting said center sill with the inner wall of said draft sill, the outer wall of said draft sill and forward wall of said bolster being curved toward each other and merging to form a continuous arcuate wall connecting said draft sill and bolster. 20. A railway vehicle underframe casting having an integral side sill in the form of a box girder with its side walls delimiting its top and bottom walls. 21. A railway vehicle underframe casting having an integral side sill in the form of a box girder with its side walls delimiting its top and bottom walls.

a box girder deeper at its central portion than at its ends and with its side walls delimiting its top and bottom walls.

22. A one-piece casting comprising a vehicle underframe with box-shaped side sills terminating short of the end of the underframe, and box-shaped bolsters extending between the ends of said side sills.

23. In a hopper car underframe casting, box-shaped side sills providing a hopper opening between them intermediate their ends, transverse members at each end of said opening and bolsters spaced from said members, the ends of said bolsters being connected to said sills.

24. A hopper car underframe comprising in an integral structure widely spaced box shaped side sills, there being a hopper opening between said side sills for accommodating the discharge of the entire car load.

In testimony whereof I hereunto affix my signature this 11th day of April, 1928.

WILLIAM M. SHEEHAN.
